UNITED STATES PATENT OFFICE.

THOMAS OLINGER, OF HOLLAND, MICHIGAN, ASSIGNOR TO HOLLAND LIGHTING & SPECIALTY CO., OF HOLLAND, MICHIGAN, A CORPORATION OF MICHIGAN.

AIR-RELEASE CAP FOR GAS-BELLS OF ACETYLENE-GENERATORS.

1,283,875.

Specification of Letters Patent.

Patented Nov. 5, 1918.

Application filed February 23, 1918. Serial No. 218,804.

To all whom it may concern:

Be it known that I, THOMAS OLINGER, a citizen of the United States of America, residing at Holland, in the county of Ottawa 5 and State of Michigan, have invented certain new and useful Improvements in Air-Release Caps for Gas-Bells of Acetylene-Generators; and I do hereby declare the following to be a full, clear, and exact description of the invention, such as will enable others skilled in the art to which it appertains to make and use the same.

This invention relates to an air release cap particularly adapted for application to 15 gas containing bells of acetylene generators. It is an object and purpose of my invention to provide a cap of this construction which may be entirely removed from the gas bell, so that on installation of the generator, or 20 whenever it is recharged, the air within the bell may be permitted to escape, the cap being put in place when the bell is filled sufficiently with gas to drive the air therefrom. A further object of the invention resides in 25 the provision of means in the cap construction for releasing, at any time, the automatic carbid feed and emergency valves, so that a ready operation of the generator may be had if the main supply of carbid has been 30 exhausted and the reserve supply has been emptied into the main carbid container. Various novel features of construction and arrangement of parts to secure these ends, as well as others not specifically mentioned 35 at this point, will appear as understanding of the invention is had from the following description, taken in connection with the accompanying drawings, in which,

Figure 1 is a vertical section through the 40 upper part of an acetylene generator equipped with my invention.

Fig. 2 is an enlarged vertical section through the air release construction comprising my invention.

Fig. 3 is a plan view of the construction 45 shown in Fig. 2.

Fig. 4 is a plan view, on a reduced scale, of the cap plate used in the construction.

Fig. 5 is a side elevation showing the complete cap plate with the operating devices 50 thereon, and

Fig. 6 is an underplan view, somewhat enlarged, of the movably mounted cam lever member which is operated to control the 55 carbid valve rod or stem.

Like reference characters refer to like parts in the different views of the drawings.

My invention may be applied to various types of acetylene generators, one of which, 60 as shown in Fig. 1, comprises a tank 1 in the lower part of which, water, as indicated at 2, is held. Above the water an inner cylindrical member 3 is located, said member adjacent its lower edges having a horizontal annular flange 4 which extends to and is secured in any suitable manner to the inner sides of the tank 1. Between the member 3 and the tank 1, depending sides 5 of a gas bell are adapted to extend, passing 65 into any suitable water seal 6 which is provided by filling water between the member 3 and the inner sides of the tank, as shown. The carbid container 7 is inserted into the upper end of the cylindrical member 3, being supported by suitable arms or clips 8 fastened to its sides and hooking onto the upper edges of said cylindrical member 3. A valve rod or stem 9 is positioned vertically in and extends through the carbid container, being normally elevated to an upper position by a weighted lever 10 which is 70 pivotally connected thereto at one end as shown. The carbid container at its lower end has an opening for the passage of carbid, rod 9 extending therethrough and having lower and upper valves 11 and 12 attached thereto, the former of which is the regular carbid feed valve, while the latter is an emergency valve. Normally, when the 75 bell is partially filled with gas sufficient to elevate the same above the upper end of the rod 9, the weighted lever 10 lifts the same until the opening in the carbid container is closed by the lower valve 11. As gas is 80 taken from the bell, it drops until its engagement with the rod 9 depresses the same, thereby lowering the carbid control valve 11 to permit the passage of pieces of carbid into the water for the generation of gas, 85 whereupon the bell is again lifted and the passage of carbid stopped. This principle 90 of automatic operation is well known in acetylene generators and is carried out in various ways.

A reserve supply of carbid is contained within a receptacle having walls 13 and a hinged bottom 14, the receptacle being secured in the top of the main carbid container. A handle 15 engages with the bot- 100 105 110

tom 14 and by turning the same, the bottom is freed to drop and permit the reserve supply of carbid to empty into the main carbid receptacle. The handle is turned by the engagement against it of a block 16, fastened on the inner side of the gas bell, the bell being turned about a vertical axis to bring the block against the handle.

In the center of the top 17 of the gas bell, 10 an opening is made and a cylindrical neck 18 of sheet metal is fastened to the top surrounding the opening and extending a short distance above the top of the bell. At the upper edges of the neck 18 an annular ring 15 19 is secured which is fashioned on its under side with an annular groove 20, best shown in Fig. 2. The upper end of the neck 18 is adapted to be closed by a cap plate 21, on the under side of which a downwardly projecting annular rib 22 is made, adapted to come into engagement with any suitable gasket 23 seated in the upper part of the ring 19. The plate 21 is formed with two oppositely extending ears 21^a through each of 25 which a rod 24 passes, each formed at its lower end with a hook 25 adapted to extend into the groove 20. The upper part of each rod 24 is threaded to receive a wing nut 26, it being evident that on tightening the nuts 30 26, the rib 22 on plate 21 is brought against the gasket 23, this making a firm and gas-tight cover for the neck 18, yet one which can be very easily removed on loosening the wing nuts.

35 A rod 27 passes loosely through the plate 21 carrying a plunger 28 at its lower end, and being formed with a head 29 at its upper end above the plate 11 adapted to rest on any suitable gasket 30 interposed between 40 said head 29 and the cap plate 21. A lever 31 formed on its under side at each end with inclined cam surfaces 32 is pivotally mounted at 33 on the cap plate, closely adjacent the head 29, and may be turned so that the 45 cam surface 32 at one end passes over the head 29, the similar cam surface 32 at the opposite end riding on a suitable rib 34 formed integral with and projecting from the plate 21. The turning of the lever 31 is accomplished through engagement of the 50 fingers with suitable wings 35 which project upwardly from the lever.

At installation, the carbid receptacle having been put in place, the plate 21 is removed 55 and the gas bell is lowered into place over the carbid receptacle, the air within the bell passing outwardly through the neck 18. There is still some air left in the bell which may be forced out by pushing down on the 60 valve rod 9 a few times, the gas which is rapidly generated driving out the air, after which plate 21 may be put in place and the upper end of the neck 18 closed tightly by tightening the thumb nuts 26. The lever 65 31 is turned to bear upon the head 29 of

rod 27 so that whenever, in use, gas is taken from the bell, causing it to lower, plunger 28 comes into engagement with the upper end of the valve rod 9 to automatically feed more carbid to the water. The same operation is gone through whenever the generator is recharged, it being necessary in recharging to remove the bell and the carbid receptacle and then replace the same after the receptacle has been filled with 75 carbid.

When the carbid from the main receptacle 7 is completely exhausted, the gas has a tendency to flow from the bell as long as possible creating a partial vacuum within the 80 bell. It will be obvious under these conditions that the bell drops to its lowest position and the emergency valve 12 is brought to substantially the position shown in Fig. 1, completely closing the passage for the 85 carbid to the water, whereupon, when the reserve receptacle is emptied into the main receptacle for carbid, no gas can be generated until in some manner the rod 9 has been elevated to raise the emergency valve 90 12. Heretofore it has been a common practice to lift the bell by hand, but owing to the partial vacuum within the same, this is not very easily accomplished. With my invention, after the reserve receptacle has been 95 dumped, all that is necessary is to turn the lever 31 to substantially the position shown in Fig. 3, this freeing the rod 27 for upward movement which, together with the rod 100 9, is elevated by the weighted lever 10 permitting the passage of some of the reserve carbid to the water and thus providing a generation of gas to enter the bell. As soon as the bell lifts so that rod 27 and the plunger 28 are freed to drop to their normal 105 position, the locking cam lever 31 may be turned to bear against the head 29 of the rod 27, thus effecting a continuation of the automatic feed action until the reserve carbid supply is exhausted.

110 A construction as described renders the operation of acetylene generators much easier than heretofore. It is of relatively simple and inexpensive construction. Various changes in minor detail of construction 115 may be resorted to without departing from the invention, and I, accordingly, do not wish to be limited to the exact structure shown and described, but consider myself entitled to all modifications of structure falling within the scope of the appended claims defining the invention.

I claim:

1. In an acetylene generator, a carbid container, a valve rod extending above the 125 same adapted to control the passage of carbid therefrom, means normally elevating the rod, a gas bell positioned over the container, said bell having an opening in its upper side, a detachable cover normally closing the 130

opening and positioned directly above the upper end of the valve rod, means carried by said cover adapted to engage with the upper end of the valve rod on lowering of the bell to depress the rod, substantially as described, and means for freeing said means to permit the same to elevate when it engages against the valve rod without depressing the same, substantially as described.

10 2. In an acetylene generator, a carbide container, a valve rod movably mounted on and extending above the same adapted to control the passage of carbide therefrom, means normally elevating the rod, a gas bell movably positioned over said container, said bell having an opening in its upper side, a cover plate for said opening, a lever pivotally mounted on the cover, and means movably mounted on the cover adapted to engage 20 with the upper end of the valve rod to depress the same on lowering of the bell, said means being free to elevate on movement of the lever to one position and being held against elevation on movement of the lever 25 to another position, substantially as described.

3. In an acetylene generator, a carbide container, a valve rod movably mounted on and extending above the same, adapted to control the passage of carbide therefrom, means normally elevating the rod, a gas bell having an opening in its upper side movably positioned over the container, a cover for the opening directly over the valve rod, means 35 movably mounted on the cover to engage with the valve rod and depress the same on lowering of the bell, and means movably mounted on the cover to engage with and hold said first mentioned means from movement when in one position, but freeing said means when in another position, substantially as described.

4. In an acetylene generator, a gas bell having a top provided with an opening 45 therein, a detachable cover plate for the opening, a rod passing loosely through the plate, a plunger head at the lower end of the rod, a head on the upper end of the rod, and means movably mounted on said plate 50 to engage with the head on the upper end of the rod in one position of said means, and freeing the rod for movement, in another position thereof, substantially as described.

5. In an acetylene generator, a gas bell having a top provided with an opening 55 therethrough, a neck secured to the top and extending upwardly therefrom, a cover plate detachably connected to the neck at its upper end, a rod passing loosely through said plate, the upper end of the rod having a 60 head adapted to bear against the plate, a lever pivotally mounted on the plate and adapted to turn over the head of the rod, and a plunger at the lower end of the rod, substantially as described. 65

6. In an acetylene generator, a gas bell having a top provided with an opening therethrough, a neck secured to the top and extending upwardly therefrom, a ring formed with an annular groove on its under 70 side secured to the upper end of the neck, a plate adapted to close the upper end of the neck, threaded rods having hooks at their lower ends passing through the plate with the hooks seated in the groove, nuts threaded 75 on the rods above the plate, a plunger located in the neck, a plunger rod passing loosely through the plate and having a head at its upper end, and means movably mounted on the plate to detachably engage with 80 the head of the rod, substantially as described.

7. In an acetylene generator, a gas bell having a top provided with an opening therein, a neck secured to the top around 85 said opening and extending upwardly therefrom, a ring having an annular recess on its under side secured to the upper end of the neck, a gasket carried by the ring around said neck, a plate located above the neck, an 90 annular rib depending from the plate and adapted to bear against said gasket, a plurality of rods passing through the plate and having hooked lower ends engaging in said groove in the ring, nuts threaded on to said 95 rods to draw the rib tightly against the gasket, a plunger rod having a plunger at its lower end passing loosely through the plate, a head to the rod above the plate, and means movably mounted on the plate to engage 100 against the head to hold the plunger in lower position, said means being movable to disengage from and free the plunger, substantially as described.

In testimony whereof I affix my signature. 105
THOMAS OLINGER.
